ASH TRAY

William B. Bailey, Mercury, Nev.

Application December 21, 1953, Serial No. 28,133

Term of patent 3½ years

(Cl. D85—2)

Fig. 1

I claim:

The ornamental design for an ash tray, as shown.
